UNITED STATES PATENT OFFICE.

RICHARD WOLFFENSTEIN AND JAMES COLMAN, OF BERLIN, GERMANY, ASSIGNEES
TO ACTIEN GESELLSCHAFT FÜR ANILIN FABRIKATION, OF BERLIN, GERMANY.

HAIR-DYE.

1,019,576.

Specification of Letters Patent.

Patented Mar. 5, 1912.

No Drawing.

Application filed May 17, 1910. Serial No. 561,870.

To all whom it may concern:

Be it known that we, RICHARD WOLFFENSTEIN and JAMES COLMAN, the former a subject of the Emperor of Germany, the latter a citizen of the United States of North America, residing at Berlin, Germany, our post-office addresses being; the former Meinekestrasse 24, Berlin, W. 15, and the latter Kurfürstendamm 200, Berlin, W. 15, have invented certain new and useful Improvements in Hair-Dyes, of which the following is a specification.

It is well known that aromatic diamins and more particularly para-phenylenediamin are much used for the production of hair dyes; but these dyes possess a great disadvantage in that the action of their bases produces an irritating effect on the human skin. This disadvantage is of great importance because some individuals are remarkably sensitive to such irritation. Our present invention overcomes this and other disadvantages and is based on the surprising discovery that the irritating effect of such diamins can be avoided if these diamins, before they are applied to the hair, are incorporated with a larger proportion of a normal sulfite, such for instance, as sodium sulfite. The result is that we can produce improved hair dyes which have no such irritating effect on the human skin and which can be used by any one.

In order to obtain such an improved hair dye, 2 parts by weight of the respective diamin, as for instance para-phenylenediamin or para-toluylenediamin, are incorporated with 1 part by weight of normal anhydrous sodium sulfite, or with another soluble alkali sulfite. If such a hair dye is applied to the hair in an aqueous solution and in the presence of a suitable oxidizing agent, very fast and beautiful tints, and more especially, black tints are obtained without any irritating effect on the human skin. In order to avoid such irritating effect, it is, however, safer to increase the addition of sulfite beyond the above-given quantity, which is to be regarded as a minimum.

The following examples may serve to illustrate our invention, the parts being by weight:

(1) As an example of our improved hair

dyes in solution, the following may be given. 9 parts of para-toluylenediamin

$(CH_3:NH_2:NH_2 = 1:2:5)$

and 9 parts of anhydrous normal sodium sulfite are dissolved together in 82 parts of water. This solution represents our new composition of matter and it may be used for dyeing purposes, for instance as follows: The concentrated solution as above obtained is mixed with 200 parts of a hydrogen peroxid solution of 3% strength. This mixed solution represents the improved hair dye ready for use, which use consists in applying the solution to the hair for instance by means of a brush, and in a short time, a fine and deep black will develop.

(2) Our improved hair dye in the dry state, according to the present invention, may be obtained for instance by finely pulverizing 10 parts of para-phenylenediamin and incorporating therewith 10 parts of anhydrous normal sodium sulfite, for instance by thoroughly grinding together the two products. In order to use this improved hair dye, it may be dissolved in water, a suitable quantity of hydrogen peroxid may be added, and the dye may be applied to the hair in the usual manner.

It is obvious that our present invention is not limited to the foregoing examples or to the details given therein. For instance, the proportions of the respective diamin and of the normal sulfite may be varied. Furthermore, instead of para-phenylenediamin and para-toluylenediamin, any other aromatic para-diamin suitable for the purpose of our present invention may be employed. Finally, instead of the normal anhydrous sodium sulfite employed above, the equivalent proportion of the crystallized salt or another normal alkali sulfite, either crystallized or anhydrous, may be used.

The shades obtained with our improved hair dye naturally depend largely upon the special nature of the hair to be dyed; and, on the other hand, the concentration of the improved dyes also has a great influence upon the resulting shade, thus, for instance, brown or blonde tints can be obtained by

employing more or less dilute solutions of the dyes.

What we claim is:—

1. As new compositions of matter improved hair dyes derived from an aromatic para-diamin comprising an aromatic diamin and a normal alkali sulfite in such proportion that to two parts by weight of the diamin they contain at least one part by weight of an anhydrous normal alkali sulfite of the formula: Me_2SO_3 , in which formula Me stands for an alkali metal.
2. As new compositions of matter improved hair dyes comprising para-toluylenediamin and a normal alkali sulfite in such proportions that to two parts by weight of the diamin they contain at least one part by weight of an anhydrous normal alkali sulfite of the formula Me_2SO_3 , in which formula Me stands for an alkali metal.
3. As a new composition of matter improved hair dyes in solution comprising

para-toluylenediamin and a normal alkali sulfite in such proportion that to two parts by weight of the para-toluylenediamin they contain at least one part by weight of an anhydrous normal alkali sulfite of the formula Me_2SO_3 , in which formula Me stands for an alkali metal.

4. As a new composition of matter an improved hair dye in solution comprising 9 parts of para-toluylenediamin

9 parts of anhydrous normal sodium sulfite and 82 parts of water.

In testimony whereof we have hereunto set our hands in presence of two subscribing witnesses

RICHARD WOLFFENSTEIN.
JAMES COLMAN.
